BASE FOR TABLE LAMPS

Edwin I. Cole, Eagle, Wis., assignor to The Stiffel Company, Chicago, Ill., a corporation of Illinois

Application August 19, 1954, Serial No. 31,920

Term of patent 7 years

(Cl. D48—20)

Fig. 1.

Fig. 2.

To all whom it may concern:

Be it known that I, Edwin I. Cole, a citizen of the United States of America, residing at Eagle, Walworth County, Wisconsin, have invented a new, original, and ornamental Design for a Base for Table Lamps, of which the following is a specification, reference being had to the accompanying drawing, forming a part hereof.

The dominant features of my design are shown in solid lines.

I claim:

The ornamental design for a base for table lamps, as shown and described.
